Primary Examiner—T. Chase Nelson*Assistant Examiner*—Karen Acker*(74) Attorney, Agent, or Firm*—Schweitzer Cornman Gross & Bondell LLP(57) **CLAIM**

The ornamental design for a grommet, as shown and described.

DESCRIPTION

FIG. 1 is a perspective view of the grommet of the invention; FIG. 2 is a top plan view of the grommet of FIG. 1;

FIG. 3 is a bottom plan view of the grommet of FIG. 1;

FIG. 4 is an end elevation view of the grommet of FIG. 1, the other end being identical;

FIG. 5 is a side elevation view of the grommet of FIG. 1, the other side being identical;

FIG. 6 is a perspective view of a second embodiment of the invention;

FIG. 7 is a top plan view of the grommet of FIG. 6;

FIG. 8 is a bottom plan view of the grommet of FIG. 6;

FIG. 9 is an end elevation view of the grommet of FIG. 6, the other end being identical; and,

FIG. 10 is a side elevation view of the grommet of FIG. 6, the other side being identical.

The broken lines are intended to show environmental structure and form no part of the claimed design.
